(57) **CLAIM**

The ornamental design for a plastic fly trap, as shown and described.

DESCRIPTION

FIG. 1 is a front view perspective of a plastic fly trap, embodying my new design;

FIG. 2 is an isometric view thereof;

FIG. 3 is a top view thereof; and,

FIG. 4 is a front cross-sectional view shown along line 4-4 of FIG. 3.

Being mirrored on all vertical planes passing through the designs center views typically referenced by right side view, rear view and left side view are identical to FIG. 1 and have been omitted.

The bottom is flat and unadorned.
